FIRE EXTINGUISHER

Filed Sept. 23, 1925

FIG. 2

FIG. 3

INVENTOR.
G. W. MOFFITT.
BY Joseph B. Gardner
ATTORNEY.

UNITED STATES PATENT OFFICE

GEORGE W. MOFFITT, OF OAKLAND, CALIFORNIA

FIRE EXTINGUISHER

Application filed September 23, 1925. Serial No. 58,043.

My invention relates to a fire extinguisher of the type in which appropriate charges of liquids are arranged to be mixed so as to produce what is known in the art as a "foam".

An object of the invention is the production of a particularly compact apparatus comprising a simple tank unit in which are included, as structural parts thereof, the various receptacles for containing and for 10 the mixing of the liquid charges.

Another object of this invention is to provide a fire extinguisher of the character described which will be particularly efficient as to construction and operation inasmuch as 15 the several chemical compartments are normally sealed but simultaneously and continuously discharge into a mixing chamber upon a simple rotative displacement of the single tank in which all said compartments 20 and the chamber are provided, and said compartments are automatically re-sealed when the tank is restored to normal position.

The invention possesses other objects and features of advantage, some of which, with 25 the foregoing, will be set forth in the following description of the preferred form of my invention which is illustrated in the drawings accompanying and forming part of the specification. It is to be understood that 30 I do not limit myself to the showing made by the said drawings and description, as I may adopt variations of the preferred form within the scope of my invention as set forth in the claims.

35 Referring to said drawings:

Figure 1 is a longitudinal sectional view showing the fire extinguisher of my invention inoperatively disposed.

Figure 2 is a sectional view taken on the 40 line 2-2 in Figure 1.

Figure 3 is an enlarged fragmentary view showing the valves and mixing chambers of the device operatively disposed.

Figure 4 is an enlarged fragmentary view 45 showing another embodiment of a portion of the device.

In an apparatus designed to produce a fire smothering foam by effecting a mixture of different non-acid or acid liquids, it has 50 been the usual practice to provide separate

containers for the various liquids and to mix such liquids only in the delivery pipe. Such an arrangement has necessitated the use of an independent means for causing the flow of liquids from the respective tanks, and as a result the necessary apparatus has been both bulky and complicated and its use has been practically limited to built-in installations. On the other hand, complete mixing of the entire charges of the liquids in one or both 55 of the tanks at one time, would result in the generation of an excessive pressure and the instantaneous rather than continuous production of the foam. It will thus be noted that the use of apparatus, such as the ordinary acid-soda type, in which the charges would be thus mixed, is not practicable. In accordance with my invention, however, a compact and unitary structure is provided 60 in which liquids which react to produce a 65 gas-charged fire smothering foam are arranged to have portions of their charges mixed only as the foam is used, and in which the pressure of the gas primarily generated 70 is utilized to eject the foam from the 75 apparatus.

To produce a structure having the hereinbefore mentioned qualities of compactness and simplicity, I utilize, as here shown, a cylindrical tank 6, such tank being mounted for rotation about its axis on axially aligned stub-shafts or trunnions 7 and 8 provided at opposite ends of the tank. In order that a single tank unit may in itself serve to provide compartments for the different liquids 80 in the simplest possible manner, the tank cavity is divided into compartments 11 and 12 by means of a plate 9 fixedly positioned in the tank and arranged transversely thereof. The plate is so located that the ratio of the 85 capacities of the compartments is in the desired ratio of mixing of the liquids to be placed therein. In this manner, it will be noted, a pair of independent compartments is provided in desired juxtaposition without necessitating the use of the two distinct tanks 90 heretofore included in extinguisher units.

Preferably arranged to lie in the plane of the partition, and extending outwardly of 95 the tank, is a chamber 13 which is here shown 100

defined by and between a flange 14 fixed to the wall 16 of the tank, a threaded cap 17 arranged to operatively engage the flange 14, and a depressed portion 18 of the tank wall centrally of which the partition terminates. The chamber 13, it will now be noted, is arranged to serve in the double capacity of a mixing chamber and a sump for the fluid, and the wall portion is accordingly perforated to provide a pair of inlet passages 21 and 22 respectively opening from the compartments 11 and 12 of the tank, and a discharge opening 23 through which a discharge pipe 24 is arranged to extend. In this manner, when the tank is disposed with the chamber 13 extending upwardly therefrom, and the compartments charged with their respective liquids to the same level, the mixing of such liquids will be prevented, but when the tank is rotated to position the chamber 13 in depending position with respect to the tank, the fluids of the compartments will flow into the chamber in proportion to their respective volumes to become mixed therein, and the gas pressure created will be exerted to force the resulting foam from the chamber into the discharge pipe 24.

In order to prevent the mixing of the fluids by splashing when the apparatus is inoperatively disposed, the passages 21 and 22 are preferably arranged to be closed by suitable one-way valves such as the clack valves 26 here shown, such valves being arranged to open upon the operative positioning of the tank. Baffle plates 27 may also be fixedly positioned in front of the valve openings, as here shown, to assist in preventing the opening of the valves by the direct splashing of liquid thereagainst. It will now be noted that the rotation of the tank back to its normal inoperative position will immediately stop further mixing of the charges as between the compartments, so that the production of foam and gas will thereupon tend to be discontinued, it being noted that the valves 26 serve, under such circumstances, to vent the compartments and thereby prevent the generation of undue pressure therein.

The discharge pipe 24, it will be noted, preferably terminates adjacent the chamber cap 17, and is here shown extending through the compartment 11 to the outer end 28 of the tank and thence through the shaft 7 to be secured in a suitable manner to a distributing pipe or hose 29. To assist an operator in rotating the tank, a handwheel 31 is preferably fixed on the end 32 of the shaft 8, the latter being preferably diametrically perforated to receive a pin 33 arranged to engage the bearing cap 36 for holding the tank against rotation in either the operative or inoperative positions. The tank and mixing chamber may, if desired, be provided with a lining formed of lead or other chemically resistant material. In the event that

it may not be desirable to permit the distributing hose 29 to act as a vent passage following a use of the device, a gas relief valve may be provided to allow the escape of gas from the chamber 13, a relief valve 38 being here shown connected to the discharge pipe 24 externally of the tank.

An acid bottle 41 may also be included in the structure, such bottle being preferably arranged to be removably mounted in an externally opening receptacle 42 provided in the wall of one of the compartments and communicating therewith, said bottle being arranged to discharge at the same side of the tank as is the chamber 13. The bottle 41 is preferably provided with a lead stopper 43, arranged either to be held seated or to be left free to be displaced upon the inversion of the bottle, so that the apparatus may be used with various combinations of chemical charges as may be desired.

In the embodiment of Figure 4, the portion 18' of the tank wall 16' defining one side of the chamber 13' is not depressed, so that the partition 9' may be of the form of a complete circle, and a still further simplified tank structure thus results.

I claim:

1. In a chemical fire extinguisher, a tank mounted for rotation about a fixed axis and partitioned to provide a plurality of normally sealed compartments therein, a chamber provided with an outlet arranged to receive charges from all of said compartments upon the rotative displacement of said tank, and means automatically operative to seal said chamber from said compartments upon a return displacement of the tank to its primary position.

2. In a chemical fire extinguisher, a tank mounted for rotation about a fixed axis and partitioned to provide a plurality of normally sealed compartments therein for the reception of different chemical solutions, a chamber provided with an outlet fixedly associated with said tank and connected to said compartments by normally closed passages, valves in said passages arranged to open upon rotative displacement of said tank to permit charges of solution from said compartments to enter said chamber, and become mixed therein, said valves being arranged to close upon a restoring of the tank to its normal position.

3. In a chemical fire extinguisher, a generally cylindrical tank mounted for rotation about the axis thereof and partitioned axially to provide a plurality of normally sealed compartments arranged to receive charges of different chemical solutions which are adapted to react when mixed to produce a gas charged fire smothering foam, a chamber fixedly associated with said tank and protruding radially outwardly therefrom with respect to said axis of rotation, passages con-

necting said chamber with said compartments, one-way valves arranged to permit the flow of liquid from said compartments to said chamber only when said chamber is disposed to extend downwardly of said tank, and a passage leading from said chamber through which the contents thereof are arranged to be discharged by reason of the pressure of the gas generated upon the mixing of the solutions in the chamber.

10 4. In a chemical fire extinguisher, a tank mounted for rotation about a horizontal axis and partitioned to provide a plurality of normally sealed compartments therein, a chamber provided with an outlet carried by said tank and arranged to receive charges from all of said compartments upon a rotative displacement of said tank, and gravitationally controlled valve means operative 15 to permit the flow of liquid from said compartments to said chamber only when said chamber is disposed to extend downwardly of said tank and to seal said chamber from said compartments when said tank is in normal position.

20 In testimony whereof, I have hereunto set my hand at Oakland, California, this 16th day of September, 1925.

GEORGE W. MOFFITT.
